BOILER FEED WATER REGULATION

Filed March 28, 1942

UNITED STATES PATENT OFFICE

2,376,029

BOILER FEED WATER REGULATION

Julian A. Campbell, Long Beach, Calif.

Application March 28, 1942, Serial No. 436,592

4 Claims. (Cl. 122—451.1)

This invention has to do generally with liquid level control apparatus, e. g. for boiler feed water regulation, in which the feed water control valve is operated in response to displacement of an element movable in accordance with changes in the boiler water level. Although independent in certain aspects of the particular type and form of primary control element whose movements regulate the operation of the feed control valve, the invention aims particularly to provide improvements in regulating apparatus of the expansible tube type as shown in United States Letters Patent No. 2,207,214, issued July 9, 1940, to me on Boiler feed water control, and in my later issued Patent No. 2,284,130 granted May 26, 1942, on Boiler feed control.

One of my principal objects is to provide an improved mechanism for operating the feed water control valve, permitting the use of valves, for example globe valves, capable of most sensitive throttling of the feed water stream and yet imposing the least restriction to flow under normal conditions. It is also proposed to minimize valve stem leakage and the possibility of stem corrosion that so frequently interferes with the necessary free operation of the valve. In accordance with the invention, axial movement of the valve stem to effect opening and closing movements of the valve is accomplished to particular mechanical advantage, with minimum friction, and independently of the usual stem propulsion screw threads in the valve structure. In fact, such threads may be entirely eliminated.

Considering the expansion tube as typical of any suitable movable element responsive to the boiler water level changes, operation of the feed water control valve occurs by a connection between the valve stem and the expansion tube producing rotation of the stem, and a cam device producing axial movement of the stem by virtue of its rotation. Preferably, I employ a rack-and-gear type of connection between the expansion tube and valve stem, gaining the advantages of a positive connection between the parts, while allowing axial or longitudinal movement of the valve stem. A further advantage of this type of connection is that it permits continued displacement of the expansion tube in a valve-closing direction, after the feed water control valve has become fully closed, all as will hereinafter appear. The cam device has the advantage of minimized friction, and therefore greater sensitivity and freedom in the valve stem movement than is possible with the usual screw thread operated stems. Incidentally, the word "cam" as

used in the claims is not intended to be inclusive of the usual interengaging threads on the valve stem and the valve body.

Another feature of the invention is the provision of a manually operated control for subjecting the upper portion of the expansion tube to cooling, for the purpose of restoring the tube to normal condition after abnormal expansion resulting from blowing-down the tube. From time to time it may be necessary to blow-down the tube to prevent excessive accumulations therein of hardened scale-forming substances tending to interfere with proper operation of the tube. As will appear, the tube may be purged by closing its water line connection with the boiler, and sweeping the tube with steam, or the water line may be left open and a mixture of steam and water blown from the tube, however without excessive water loss. After the tube blow-down, hot water then rushes into the tube from the boiler, tending to excessively expand the tube unless the latter is promptly cooled. In accordance with the invention, excessive expansion of the tube is prevented by introducing directly into the upper interior of the tube a cooling fluid, preferably water from the feed line, only for a short interval of time required for reduction of the tube temperature to normal.

In Patent No. 2,284,130, I disclose a system for cooling the expansion tube by maintaining a more or less continuous flow of water into the tube under control of a valve operated automatically in accordance with movements of the feed water regulating valve. The present tube cooling system is to be distinguished in that normally no flow of water occurs into the tube, and cooling thereof is to be accomplished by opening the manually controlled valve only at such times as the tube is to be contracted after an abnormal expansion, say following the tube blow-down.

All the various features and objects of the invention will be understood to better advantage from the following detailed description of the invention as embodied in the typical and illustrative form shown in the accompanying drawing, and in which:

Fig. 1 is a general view showing the apparatus connected to a conventionally illustrated boiler;

Fig. 2 is an end elevation of the regulator assembly;

Fig. 3 is an enlarged cross-section on line 3—3 of Fig. 2;

Fig. 4 is a section on line 4—4 of Fig. 3; and

Fig. 5 is a fragmentary view showing the rack

and gear connections between the expansion tube and feed water valve stem.

Referring first to Fig. 1, the part of the regulator primarily responsive to liquid water level changes in the conventionally illustrated boiler 10, comprises a tube 11 made of brass or other suitable metal rendering the tube longitudinally expansible in accordance with its temperature changes resulting from variations of the water level within the tube. It will be understood that the tube may be mounted in any suitable position so that the water level normally stands in the tube intermediate its ends. Typically, the tube is shown to be placed in an inclined position with the upper and lower ends of the tube connected with the steam chamber and water space in the boiler, respectively, by a flexible conduit 12 and pipe 13. The connection at 14 between conduit 12 and the expansion tube may consist of a coupling 15 attaching the conduit to fitting 16 threaded into a hollow casting 17 on the end of the tube. Arm 18 projecting from the casting 17 may be connected with other apparatus, such as a signaling system, not shown, to be operated by or in accordance with the movements of the expansion tube 11. The lower end of the tube is attached by fitting 19 to a suitable frame structure 20 comprising an upright member 21 and base angle iron 22, these members being interconnected by a diagonal brace 23. Casting 17 is pivotally connected at 24 with a rod 25, the opposite end of which is attached at 26 to support 21 by way of an adjustable yoke, generally indicated at 27.

As will be understood, the water normally stands in tube 11 at a level L—L' intermediate its ends, the upper interior of the tube above the water level being directly exposed to steam communicated through conduit 12. Upon lowering of the water level, the tube expands due to the increased length of heating by direct contact with the steam, producing, by virtue of the rigid rod connection 25, upward lateral deflection of the tube and its later described connection with the feed water control valve. As the water level rises in the tube, the cooling effect causes its contraction and downward deflection of the tube and rod assembly. Heat radiation from the lower extent of the tube may be increased considerably by use of fins 28, the particular advantages of which are discussed in greater detail in the first issued patent referred to hereinabove.

Feed water is supplied to the boiler through line 30 under control of valve 31 operated in accordance with movements of the expansion tube 11. The invention is primarily concerned with the operating mechanism, generally indicated at 32, by means of which lateral movements of the expansion tube produce opening and closing movements of the feed control valve 31. As shown particularly in Figs. 2 and 4, the valve 31 is operated by a stem 33 which may be formed integrally with a shaft 34 having a rack and gear connection at 35 with rod 36 pivotally attached at 37 to casting 17 on the end of the expansion tube. Referring to Fig. 5, the connection 35 between the valve stem 33 and rod 36 comprises a gear 38 fixed to shaft 34 and engaging a rack 39 carried by and movable with relation to rod 36. The rack has a longitudinal bore 40 through which rod 36 is inserted, and normally the position of the rack with relation to the rod is determined by engagement of the bottom extension of the rack with nut 43. Down-

ward movement of the rod is transmitted to rack 39 by way of coil spring 41 engaged by nut 42, the spring being sufficiently strong to undergo no appreciable deformation during normal operations, and to permit vertical movement of the rack, and therefore rotation of the gear 38 and valve stem 33, in exact accordance with downward deflections of the expansion tube 11. The relative positions of nuts 42 and 43 may be adjusted to take up any looseness in the spring position on the rod, but without causing the spring at any time to undergo excessive or fatigue strains. The lower portion of rod 36 may be guided within an opening 44 in a horizontal support 45 extending between the body of valve 31 and bracket 46.

Axial movement of the valve stem 33 and attached shaft 34 in accordance with their rotation is effected by a cam mechanism, generally indicated at 48, which, together with the shaft assembly, is supported by bracket 46, the latter being attached by screws 49 to an angle base 50. As shown in Figs. 3 and 4, the cam proper comprises a cylindric body 51 clamped against rotational movement within opening 52 of the split bracket 46. The cam body is clamped endwise within the bracket by plates 53 and 54 attached to the bracket by bolts or screws 55. Shaft 34 may be journaled at 56 in a bearing formed by the plate 53, and also within a roller bearing assembly, conventionally illustrated by the dotted lines at 57, contained within a housing 58 integral with plate 54. The body 51 contains a pair of oppositely positioned, helical cam slots 59 receiving a pair of rollers 60 rotating on pin 61 carried by the shaft 34, the diameter of rollers 60 being just slightly less than the width of the cam slots 59. The angularity of the slots as viewed in Fig. 4 may, of course, be predetermined to produce the desired axial movement of the valve stem for a given degree of rotation.

In considering the operation of the valve operating mechanism 32, assume first that the water levels in the boiler and tube 11 lower to cause upward deflection of the tube and rod assembly. Such upward movement is transmitted through rod 36, rack 39, and the gear 38, to rotate shaft 34 and the valve stem 33 in exact accordance with the expansion tube deflection. The resulting rotation of rollers 60 within cam slots 59 moves the valve stem 33 toward the right, opening the feed control valve 31 to increase the rate of water supply to the boiler. As the normal water levels are restored, the end of the expansion tube and rod 36 move downwardly, such movement being transmitted through coil spring 41 and the rack-and-gear assembly 35, to reversely rotate the valve stem and cam rollers 60 and thereby move the feed control valve 60 in a closing direction. As will be understood, when the boiler and expansion tube water levels rise above normal, causing downward deflection of the tube, the feed control valve is operated by mechanism 32 in a sequence opposite to that resulting from lowering of the water levels.

Rod 36 and the spring 41 provide, in effect, a lost motion connection between the expansion tube and valve stem, permitting continued downward movement of the tube after the valve 31 has become completely closed and the tube is cooled below its lowest operating temperature, as when the boiler is shut down. Cooling of the tube 11 within a predetermined range, as previously indicated, fully closes the feed control valve 31. Thereafter, as the tube undergoes further cool-

ing, spring 41 is compressed to allow continued downward movement of the tube and rod, lowering nut 43 from engagement with the bottom end of the rack 39. This is a safety feature of importance in that it prevents deformation or injury of any parts of the equipment that might otherwise result in the absence of such provision permitting continued displacement of the expansion tube assembly beyond the closed valve position.

The mechanism 32 may carry suitable indicating means by which the operator may at any time ascertain the degree of opening of the feed water valve, and therefore the boiler load in terms of water throughput, and also at any time the condition of steaming as indicated by the boiler water level. As illustrative, the bearing housing 58 may carry a dial plate 63 having indicia in the form of a series of holes 64 visible from either side of the dial. Shaft 34 may carry a pair of indicators 65 and 66 adjustably mounted on the shaft. The relation of the indicators may be such that when valve 31 is fully closed, indicator 65 will be in a horizontal position and indicator 66 will be swung to the right or vertical a distance such that when the valve is opened to normal position (corresponding to normal water level), indicator 65 will have swung opposite the uppermost opening 64. As the valve opens and the boiler water reaches normal level, the indicators swing counter-clockwise to substantially the position shown. The operator thereafter can observe with reference to indicator 66, the condition of the boiler water level, i. e. the direction and extent of any changes from normal, caused by variations in the rate of steam generation, or for any other reason. At the same time, the position of the feed water valve, and therefore the rate of water delivery to the boiler, are shown by the position of indicator 65.

I have previously referred to the provision of a normally closed connection between the feed water line and the upper portion of the expansion tube 11, whereby water may be introduced to the tube after abnormal expansions thereof, to cool and thereby return the tube to normal elongation. Such cooling water may be delivered through a line 68 connecting with pipe 30 at the inlet side of valve 31 and connecting at 69, see Fig. 2, with the hollow casting 17 on the end of the expansion tube. Line 68 contains a valve 70 operated by lever 71, to an extension 71a of which is connected a coil spring 72 normally maintaining the valve in closed position and preventing the flow of water to the expansion tube.

When the expansion tube 11 is to be blown-down for the removal of scale and other accumulations, valve 80 in water line 13 leading to the boiler may be closed, and valve 81 opened to permit steam from line 12 to sweep through and displace the contents of the tube through the outlet 82. As an alternate procedure, both valves 80 and 81 may be opened, permitting the steam being blown through the tube and pipes to withdraw some water from the boiler, this method being preferred by reason of the effectiveness of the water and steam mixture to thoroughly flush out sediment from the valves and fittings.

After blowing-down the tube as described, valve 70 may be opened for a short while, say about ten seconds, to admit a small stream of

water directly into the upper or hot end of the tube, thus quickly cooling the tube to restore the feed water control valve to normal position and thereby avoid any appreciable change in the boiler water level.

I claim:

1. In boiler water level control apparatus including a longitudinally expansible tube adapted to be connected with water and vapor spaces in the boiler so that the water stands in the tube at a level intermediate its ends and surges therein as the boiler water level changes to produce lateral deflection of the tube, and a boiler feed water control valve; the combination comprising a stem connected to said valve, means for rotating the valve stem by lateral deflection of said tube, and a cam means connected to said stem and operable to axially move the stem in accordance with its rotation, said cam means comprising a member having a cam surface, and a roller carried by said stem and engaging said surface.
2. In boiler water level control apparatus including a member movable positively in response to changes of the boiler water level, and a feed water control valve contained within a body; the combination comprising a stem connected to said valve, yielding means for transmitting movement of said member to the stem and normally resisting deformation to produce rotation of the stem in a valve closing direction, said yielding means being deformable to permit continued movement of said member in a valve closing direction after the valve has fully closed, and cam means operable to axially move the stem in accordance with its rotation as thus produced.
3. In boiler water level control apparatus including a member movable positively in response to changes of the boiler water level, and a feed water control valve contained within a body; the combination comprising a stem connected to said valve, a bearing within which said stem is journaled at a location in spaced relation to said body, yielding means for transmitting movement of said member to the stem at a location between said body and bearing and normally resisting deformation to produce rotation of the stem in a valve closing direction, said yielding means being deformable to permit continued movement of said member in a valve closing direction after the valve has fully closed, and cam means operable to axially move the stem in accordance with its rotation as thus produced.
4. In boiler water level control apparatus including a member movable positively in response to changes of the boiler water level, and a feed water control valve contained within a body; the combination comprising a stem connected to said valve, a rack-and-gear connection between said member and stem for rotating the stem in accordance with changes of the boiler water level, said connection comprising a gear carried by the stem, a toothed rack engaging said gear, a spring for transmitting movement of said member to the rack and normally resisting deformation to produce rotation of the stem in a closing direction, said spring being deformable to permit continued movement of said member in a valve closing direction after the valve has fully closed, and cam means for axially moving the stem in accordance with its rotation.

JULIAN A. CAMPBELL.
